(57) **CLAIM**

The ornamental design for an LED bracket, as shown and described.

DESCRIPTION

FIG. 1 is a front elevational view of the LED bracket;
FIG. 2 is a rear elevational view thereof;
FIG. 3 is a bottom plan view thereof;
FIG. 4 is a top plan view thereof;
FIG. 5 is a left side elevational view thereof;
FIG. 6 is a right side elevational view thereof; and
FIG. 7 is a front perspective view of the LED bracket.
The broken lines in the drawings illustrate portions of the LED bracket that form no part of the claimed design.
